CLAIM

The ornamental design for a bagel container, as shown and described.

DESCRIPTION

FIG. 1 is a top perspective view of a bagel container showing my new design;

FIG. 2 is a top plan view thereof;

FIG. 3 is a bottom plan view thereof;

FIG. 4 is a left side elevational view thereof;

FIG. 5 is a front elevational view thereof;

FIG. 6 is a right side elevational view thereof;

FIG. 7 is a rear elevational view thereof; and,

FIG. 8 is a bottom perspective view thereof.

The broken lines showing a logo on the top of the container illustrate portions of the bagel container that form no part of the claimed design.

1 Claim, 6 Drawing Sheets
